OF HOPEDALE, MASSACHUSETTS, A CORPORATION OF MAINE.

FEELER MECHANISM FOR LOOMS.

1,405,451.

Specification of Letters Patent. Patented Feb. 7, 1922.

Application filed July 22, 1920. Serial No. 388,256.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

10 This invention relates to feeler mechanisms for looms, whereby the operative condition of the loom is changed or filling replenishment effected when the filling in the shuttle has become substantially exhausted.

15 In order to be practically efficient, feeler mechanisms must act quickly and at the same time be responsive to the presence or substantial absence of filling in the shuttle.

20 These requirements are necessitated because the feeler mechanism must act during the small fraction of time that the shuttle is in the delivering box; and should replenishment be called when a working supply of filling is still present in the shuttle, an unnecessary waste of yarn results, while on the other hand, if the filling be not replenished before complete exhaustion of that in the shuttle, imperfect cloth will be woven.

25 Many forms of feeler mechanisms have been suggested, each having for its general purpose the accomplishment of the above-stated results, and among the types of mechanisms heretofore proposed, is that known as the inclined feeler, shown and described in the patent to Edward S. Stimpson, No. 1,309,226, dated July 8, 1919. The feeler mechanism of the present invention is of this general type, and one of the purposes 30 thereof is to provide a mechanism in which the feeler is of the inclined type, and which will be effective in operation and simple in construction, and at the same time be responsive either to the presence or absence of filling in the shuttle on a detecting beat.

35 The features of the present invention and novel combination of parts will best be understood from the following description and accompanying drawings of one good, practical form of the invention.

40 In the drawings:—

45 Figure 1 is a plan view showing the feeler mechanism of the present invention and the relation of its parts when filling is present in the shuttle on a detecting beat;

Fig. 2 is a view similar to that of Fig. 1, showing the position of the parts of the feeler mechanism when filling is substantially exhausted on a detecting beat; and

50 Fig. 3 is a perspective view of the feeler mechanism showing the parts in feeling position.

The feeler of the present mechanism is supported to extend rearwardly in a direction inclined to the path of movement of the lay or, inclined to the longitudinal axis of the shuttle, and when the filling is substantially exhausted on a detecting beat, the frontward pressure upon the end of the inclined feeler tends to slide the engaging 60 end longitudinally along the filling carrier or bobbin. This movement of the feeler is permissible by reason of its support which is preferably constituted by guides on a feeler stand, and between the guides the 65 feeler is connected to spring-actuated means confining its swinging movement, or its movement longitudinally of the shuttle, about an axis which is preferably, though not necessarily, between the guides. The 70 spring-actuated means for maintaining the feeler in its rearward feeling position, yet with permissive sliding and swinging movement frontwardly and along the filling carrier, is preferably formed as a spring which 75 is supported independent of the feeler, and is connected to the feeler to exert its torsional effect through the rack and pinion connection; and means is provided which, while maintaining the rack and pinion engaged, yet permit swinging movement of the 80 feeler about the axis of the pinion.

85 It has not been deemed necessary in the drawings herein, to illustrate the filling replenishing mechanism, or the particular details of the connection between the feeler mechanism and the replenishing mechanism for effecting replenishment of filling, because such mechanism is now well understood in the art.

90 The loom frame 1, only a portion of which is indicated in Fig. 3, has connected to it adjustably a feeler carrier 2 which may be conveniently constituted by a plate having a slot 3 by which it can be adjustably 95 secured to the loom frame by means of a bolt 4.

100 Mounted on the feeler stand for sliding and swinging movement is the feeler 5 which extends rearwardly in an inclined direction, 110

and enters the shuttle on each detecting beat of the lay in a direction inclined to the path of the lay.

The feeler 5 is confined to its forward 5 and rearward and swinging movements by means of suitable guides which, in the present instance of the invention, may be formed by the bridge-pieces 6 and 7, the bridge 6 being conveniently designated as the front 10 guide, and the bridge 7 as the rear guide. It will be noted that both these guides have elongated lateral slots so that the feeler may swing in each of the guides, as well as be moved forwardly and rearwardly therein.

15 Rising from the feeler stand 2 is a stud or pin 8 on which is mounted for rotary movement a pinion 9. The pinion 9 has its teeth engaged with the teeth 10 formed as a rack and carried by the feeler, the construction being such that should the pinion 9 be rotated on its axis, the feeler 5 will be correspondingly moved or reciprocated.

20 A spring 11 is wound about the stud or pin 8, and one end of the spring, as at 12, 25 is secured in fixed position, or to the stud 8, while the other end of the spring at 13 is secured to the pinion, the torsional effect of the spring being utilized to move the feeler rearwardly into feeling position through the 30 rack and pinion connection, as above described.

The spring 11, which thus acts upon the feeler, is mounted independently of the feeler, and its axis is substantially at right angles to the plane of feeler movement. The 35 tension of the spring 11 may be varied by adjusting the stud or pin 8.

In order that the feeler may remain under the control of the torsional spring 11 as it 40 moves forwardly and rearwardly and swings longitudinally of the shuttle, provision is made for movement of the feeler laterally in the guides 6 and 7, and devices are associated with the rack and pinion 45 mechanism for holding them in engaged relation as the feeler partakes of its several movements.

In the present instance of the invention, the feeler 5 has two leg portions 14 and 15, 50 and between these leg portions of the feeler, the spring 11 and its associated connections with the feeler, are preferably located. The leg 14 has the rack teeth 10 preferably formed thereon or integral therewith. Between the leg 15 and the pinion 9 is an idle 55 rack 16, the teeth 17 of which engage the pinion 9 opposite the rack teeth 10, the construction being such that as the pinion is rotated, either by forward pressure upon 60 the feeler or by the rearward movement of the feeler under the torsional action of the spring 11, the two racks will be moved in reverse directions. Thus, when the feeler is moved forwardly on a detecting beat, as 65 indicated in Fig. 1, the rack teeth 10 turn the

pinion 9 in opposition to the spring 11 and simultaneously act upon the rack 16 to move it rearwardly. The purpose of the rack 16 is to keep the pinion and the rack teeth 10 in engaged relation with permissive movement of the feeler both longitudinally and laterally, or in a direction longitudinally of the shuttle; and in discharge of this function, it may be desirable in some cases, to substitute for the rack 16 some other form 70 of means.

The two legs 14, 15 of the feeler 5 are preferably formed by cutting out or bifurcating the forwardly-extending portion of 75 the feeler.

80 When the feeler is moved rearwardly under the action of the spring 11, it should be returned to proper feeling position, that is, to its rearward position inclined to the longitudinal axis of the shuttle. A suitable 85 stop and restoring device may be employed for this purpose, a good, practical form thereof being herein shown as a lateral projection 18 which is adapted to engage a pin 19 rising from the feeler stand 2. The projection 18 has a cam surface 20 which, as the feeler is moved rearwardly by the torsional action of the spring 11, engages the stop or pin 19 and by its inclined or cam relation with the length of the feeler, throws the 90 front end portion of the feeler laterally about the axis of the spring 11 or pinion 9 as a centre, so that the rear end portion of the feeler, which carries the teeth 21, is moved laterally in the opposite direction 95 into proper feeling position about the axis of the spring 11 as a centre.

The shuttle 22 is indicated in the drawings, but the lay, which of course is provided with the usual shuttle-box, is omitted. 100 The front wall of the shuttle is slotted as at 23, for the entrance of the feeler, and a similar slot, as usual, is formed in the front wall of the shuttle-box, but such form of shuttle-box and its slotted front wall being well 105 known, it is not deemed necessary to illustrate this detail. The shuttle 22 has the usual bobbin-holding jaws 24 which engage the usual rings on the head or base of the bobbin 25.

110 When the filling is present in the shuttle on a detecting beat, the engaging end 21 of the feeler 5 contacts with the filling, and owing to the inclined position of the feeler relative to the longitudinal axis of the shuttle, the feeler will be moved forwardly and given a slight swinging movement about the axis of the spring 11 or the pinion 9 as a centre; and owing to the toothed end engaging the filling, the feeler will not slip 115 or slide along the filling carrier or bobbin. When the filling is substantially exhausted on a detecting beat, however, the end 21 of the feeler will fail to be held from slipping longitudinally along the filling carrier or 120

- bobbin on a detecting beat, and as a consequence, the feeler will be moved by the frontward pressure into substantially the position indicated in Fig. 2, that is, its 5 toothed end will slide along the filling carrier or bobbin and it will be given a greater amplitude of movement in a direction longitudinally of the shuttle than in its normal stroke when filling is present in the shuttle.
- 10 It may also be moved frontwardly somewhat.
- In order to utilize the movement of the feeler in a direction longitudinally of the shuttle, which occurs when the filling is substantially exhausted, as above described, the 15 present invention employs connections between the feeler and replenishing mechanism to effect replenishment of filling when the feeler is thus moved. Various types of 20 connections may be employed, but in the present instance the feeler stand has pivotally mounted thereon at 26, the swinging lever 27, the rear end portion 28 of which is normally in a position to be engaged by the 25 feeler 5 only when the rear end of the feeler slips or slides along the filling carrier or bobbin on a detecting beat, so that normally the lever 27 will remain quiescent when the filling is present in the shuttle on a detecting 30 beat, but will be swung upon its pivotal support when the filling is substantially exhausted. The swinging lever 27 has connected thereto a transmitter 29 which may be formed as a rod pivotally connected to 35 the swinging lever 27 at 30.
- From the construction described it will be apparent that while the feeler is normally supported in a direction inclined to the longitudinal axis of the shuttle, and is given a 40 frontward and a swinging movement under the varying conditions of its use, its swinging movement is about a centre corresponding to the axis of the spring coils 11 or the pinion 9 with reference to which the feeler 45 may move toward and from the front of the loom, and also swinging laterally.
- What is claimed is:—
1. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 50 means actuated by the movement of the feeler along the filling carrier when the filling is substantially exhausted for effecting replenishment of filling, a spring, and rack and pinion connections between the spring and feeler constructed and arranged to move the feeler into its rearward inclined position and permit the feeler to move frontwardly and in a direction longitudinally of the shuttle. 55
2. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 60 means actuated by the movement of the feeler along the filling carrier when the filling is substantially exhausted for effecting replenishment of filling, a spring mounted independent of the feeler, and rack and pinion connections between the spring and feeler constructed and arranged to move the feeler into its rearward inclined position and permit the feeler to move frontwardly and in a direction longitudinally of the shuttle. 65
3. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 70 means actuated by the movement of the feeler along the filling carrier when the filling is substantially exhausted for effecting replenishment of filling, a spring mounted independent of the feeler, and rack and pinion connections between the spring and feeler constructed and arranged to move the feeler into its rearward inclined position and permit the feeler to move frontwardly and in a direction longitudinally of the shuttle. 75
4. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 80 means actuated by the movement of the feeler along the filling carrier when the filling is substantially exhausted for effecting replenishment of filling, a spring, a stud on which the spring is mounted, and rack and pinion connections between the spring and feeler constructed and arranged to move the feeler into its rearward inclined position and permit the feeler to move frontwardly and in a direction longitudinally of the shuttle. 85
5. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 90 means actuated by the movement of the feeler along the filling carrier when the filling is substantially exhausted for effecting replenishment of filling, a spring, a stud about which the spring is mounted, a toothed wheel to which one end of the spring is secured, a rack carried by the feeler and meshing with the toothed wheel to convert the unwinding tendency of the spring into movement of the feeler to rearward position. 95
6. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 100 means actuated by the movement of the feeler along the filling carrier when the filling is substantially exhausted for effecting replenishment of filling, a spring, a stud about which the spring is mounted, a toothed wheel to which one end of the spring is secured, a rack carried by the feeler and meshing with the toothed wheel to convert the unwinding tendency of the spring into movement of the feeler to rearward position. 105
7. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 110 means actuated by the movement of the feeler along the filling carrier when the filling is substantially exhausted for effecting replenishment of filling, a spring, a stud about which the spring is mounted, a toothed wheel to which one end of the spring is secured, a rack carried by the feeler and meshing with the toothed wheel to convert the unwinding tendency of the spring into movement of the feeler to rearward position. 115
8. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 120 means actuated by the movement of the feeler along the filling carrier when the filling is substantially exhausted for effecting replenishment of filling, a spring, the coils of which are about an axis at substantially a right angle to the plane of movement of the feeler, a member actuated by the spring 125
9. In a feeler mechanism for looms, the combination of a feeler supported in a position and for movement inclined to the longitudinal axis of the shuttle and held from movement along the filling carrier by engagement with the filling on a detecting beat until substantial exhaustion of filling, 130 means actuated by the movement of the feeler along the filling carrier when the filling is substantially exhausted for effecting replenishment of filling, a spring, the coils of which are about an axis at substantially a right angle to the plane of movement of the feeler, a member actuated by the spring

to rotate about the axis of the spring, and connections between said rotating member and feeler for urging the feeler rearwardly and adapted to permit the feeler to move 5 forwardly and also in a direction longitudinally of the shuttle.

6. In a feeler mechanism for looms, the combination of a feeler that is mounted to slide toward and from the front of the loom 10 in a direction inclined to the lay movement and that is held from movement lengthwise of the filling carrier or bobbin in the shuttle by engagement with the filling on a detecting beat until substantial exhaustion there- 15 of, a series of rack teeth carried by the feeler, a pinion engaging the rack teeth on the feeler, a spring which acts through the pinion and rack teeth to return the feeler to rearward position after it has been dis- 20 placed forwardly, and means for adjusting the tension of the spring.

7. In a feeler mechanism for looms, the combination of a feeler that is supported for swinging movement and for movement 25 towards and from the front of the loom in a direction inclined to the longitudinal axis of the shuttle, a front and a rear guide through which the feeler extends, means positioned between said guides for confining 30 the swinging movement of the feeler about an axis between the front and rear guides as the feeler is displaced by the pressure upon it, and a spring mounted at the axis of swinging movement of the feeler and adapt- 35 ed to yieldingly move the feeler rearwardly.

8. A feeler mechanism for looms, having, in combination, a side slipping sliding and swinging feeler which is moved forwardly and backwardly during the normal 40 running of the loom in a path inclined to the longitudinal axis of the shuttle and slips in a direction longitudinally along the filling carrier or bobbin in the shuttle on a detecting beat when the filling is substantially exhausted, front and rear fixed guides 45 through which the feeler extends for movement laterally and longitudinally, means between the guides for confining the swinging movement of the feeler about an axis 50 between the front and rear guides, and means acting upon the feeler to yieldingly move it rearwardly.

9. In a feeler mechanism for looms, the combination of a feeler stand having a pivot 55 pin, a feeler supported on the stand to enter the shuttle and for movement towards and from the front of the loom in a direction inclined to the longitudinal axis of the shuttle, feeler positioning means adapted to form 60 a connection between the feeler and pivot pin which permits the feeler to swing about the pin as a fixed axis and to slide relatively to the pin, and a spring adapted to actuate the feeler positioning means to move the 65 feeler rearwardly.

10. In a feeler mechanism for looms, the combination of a feeler stand, a feeler mounted on the stand for movement toward and from the front of the loom and also longitudinally of the shuttle, a rack carried by the feeler, a pinion engaging the rack, a spring connected to the pinion, and means for maintaining the rack and pinion in engagement as the feeler is given its forward, rearward, and said longitudinal 75 movements.

11. In a feeler mechanism for looms, the combination of a feeler stand, a feeler mounted on the stand for movement toward and from the front of the loom and also 80 longitudinally of the shuttle, a rack carried by the feeler, a pinion engaging the rack, a pin or stud supporting the pinion, a spring connected to the pinion, and means for maintaining the rack and pinion in engagement as the feeler is given its front- 85 ward, rearward, and said longitudinal movements.

12. In a feeler mechanism for looms, the combination of an inclined feeler, front and 90 rear guides in which the feeler may move, a rack connected to the feeler, a pinion engaging the rack between the front and rear guides, a spring normally acting through its rearward position, means for holding the rack and pinion engaged as the feeler is moved, and a stop for limiting the rearward movement of the feeler. 95

13. A feeler mechanism for looms having, in combination, a side slipping sliding and swinging feeler which is moved forwardly and backwardly during the normal running of the loom along a path inclined to the longitudinal axis of the shuttle and 100 slips in a direction longitudinally along the filling carrier or bobbin in the shuttle on a detecting beat when the filling is substantially exhausted, guides through which the feeler extends, a rotatable member operatively connected to the feeler to move it rearwardly and adapted to form a pivotal support for the feeler, a spring for rotating said member to yieldingly move the feeler rearwardly, and a shoulder upon the feeler 105 positioned to engage a fixed stop as the feeler moves rearwardly to swing the feeler about said pivot to the feeling position. 110

14. In a feeler mechanism for looms, the combination of a feeler having leg portions, 120 one of which is provided with a rack, a pinion between the leg portions engaging the rack, and means coacting with the other leg portion for holding the rack and pinion engaged during movement of the feeler. 125

15. In a feeler mechanism for looms, the combination of a feeler having leg portions, one of which is provided with a rack, a pinion between the leg portions engaging the rack, means coacting with the other leg 130

portion for holding the rack and pinion engaged during movement of the feeler, and a spring connected to the pinion.

16. In a feeler mechanism for looms, the combination of a feeler having a rack and an arm spaced from the rack, a pinion engaging said rack, an idle rack between the arm and pinion and adapted to maintain engagement between the pinion and racks, and a spring for yieldingly urging the feeler rearwardly.

17. In a feeler mechanism for looms, the combination of a side slipping, sliding, and swinging feeler which is moved frontwardly in a path inclined to the longitudinal axis

of the shuttle by engagement with the filling on each detecting beat and slips along the filling carrier or bobbin by the forward pressure upon it when the filling is substantially exhausted, a rotatable actuator 20 connected to the feeler between the front and rear ends thereof and about which the feeler may swing as a pivot, means for rotating the actuator, and means for effecting replenishment of filling when the filling is 25 substantially exhausted on a detecting beat.

In testimony whereof, I have signed my name to this specification.

ISAAC SNOW.
